DESIGN FOR A CONSOLE.

SPECIFICATION forming part of Design No. 21,250, dated December 22, 1891.

Application filed November 17, 1891. Serial No. 412,213. Term of patent 7 years.

To all whom it may concern:

Be it known that I, WILLIAM B. BIGELOW, a citizen of the United States, residing at New York, in the county of New York and State of New York, have invented a certain new and original Design for Consoles; and I do hereby declare the following to be a full, clear, and exact description of the invention, such as will enable others skilled in the art to which it appertains to make and use the same.

My invention relates to an original design for consoles for upright pianos.

The leading features of my design are the representation of a spherical portion having a series of curved projections thereon and a series of smaller curved projections intermediate of said first-mentioned projections, and a representation of a conical portion and a representation of a series of serpentine grooves therein.

The accompanying drawing represents my design.

A represents the upper portion of a console for an upright piano, on the end of which a scroll a is represented.

The upright portion B of the console is represented as comprising a spherical portion C, on the face of which is represented a series of curved projections b and a series of intermediate projections c. Below the portion C the portion D of the console is represented as being conical in form and as having a series of serpentine grooves d therein. Below the portion D the portion E is represented as a square block having a scroll in each side.

Having fully described my design, what I claim as new and original, and desire to secure by Letters Patent, is—

The design for consoles herein shown and described.

In testimony whereof I have signed this specification in the presence of two subscribing witnesses.
